MECHANICAL TOY

Casper Kreutzer, Milltown, N. J.

Application August 6, 1942, Serial No. 453,786

9 Claims. (Cl. 46—119)

This invention relates, generally, to mechanical toys; and the invention has reference, more particularly, to a novel toy provided with a mechanically actuated figure adapted to be moved relative to a suitably pictured environment.

The invention has for an object to provide a toy having a movable figure and a stationary front portion simulating an appropriate pictured environment and having a suitably disposed opening or openings through which said movable figure may be exposed, together with means for guiding the figure, and means to automatically move the figure back and forth on said guide means.

The invention has for a more specific object to provide a simply constructed mechanical toy of the character above referred to, comprising a casing having a front wall provided with an outer exposed face suitably printed or lithographed to simulate, at least in part, the appearance of a room fireplace and its chimney, and including an opening in the fireplace picture, means being provided within the casing for supporting and guiding a figure (representative of Santa Claus) for descending and ascending movements within the casing, whereby the figure, at the limit of its descending movement, is visible through said opening in the fireplace picture, and means being further provided for automatically producing alternated descending and ascending movements of the figure, whereby to provide the illusion of descent and ascent of Santa Claus through the chimney to and from the fireplace.

Another object of the invention is to further include, in the face wall design of the toy casing, a depiction of a building roof through which the fireplace chimney appears to emerge, and a depiction of a reindeer drawn sleigh upon the roof, adjacent to which the casing face wall is provided with a second opening through which the Santa Claus figure is in part visible upon completion of its ascending movement, whereby to provide the illusion of Santa Claus leaving and entering the sleigh prior to descent and subsequent to ascent through the chimney to and from the fireplace.

The invention has for a further object to provide, in a toy of the kind described, upper and lower driving means to which pull cables respectively extend from the figure, one said driving means being driven through releasable clutch means by a clock-work motor and the other being driven by stored energy of a drive spring or equivalent means, and clutch control means being provided adapted to be actuated on comple-

tion of the respective movements of the figure, whereby to effect alternated operation of the respective drive means, thereby to automatically reverse the descending and ascending movements of the figure on completion thereof.

Other objects of this invention, not at this time more particularly enumerated, will be understood from the following detailed description of the same.

An illustrative embodiment of the invention is shown in the accompanying drawing, in which:

Fig. 1 is an exterior front face view of the toy casing; Fig. 2 is a vertical longitudinal sectional view of the toy, taken on line 2—2 in Fig. 3; and Fig. 3 is a vertical longitudinal sectional view of the toy, taken on line 3—3 in Fig. 2.

Similar characters of reference are employed in the above described views, to indicate corresponding parts.

Referring to the drawing, the toy according to the invention includes a hollow casing formed by top and bottom walls 1 and 2, side walls 3 and front and back walls 4 and 5, all joined together in any suitable manner. In the illustrative embodiment of the toy, as shown, the outer face of the front wall 4 is suitably printed or lithographed to provide on its lower portion the depiction of a room fireplace 5 and the chimney 6 leading upwardly therefrom. Said front wall 4 is cut away to provide a lower opening 7 formed within the area of the back of the depicted fireplace. Preferably, the upper portion of the front wall face is printed or lithographed to provide the depiction of a building roof 8 and an exterior portion 9 of the chimney, and additionally with the depiction of a reindeer drawn sleigh 10. Said front wall is additionally cut away to provide an upper opening 10' above and contiguous to the sleigh picture. Said opening 10' may be glazed with transparent material 10'' if desired.

Arranged within the interior of the casing, to extend vertically between the top and bottom walls 1 and 2 thereof and spaced behind the front wall 4 and its lower and upper openings 7 and 10', is a guide means, preferably comprising a pair of laterally spaced perpendicular guide rods 11, the upper and lower ends of which are suitably affixed to the top and bottom walls 1 and 2 of said casing.

Slidably supported by said guide rods 11, for descending and ascending movements thereon, is a carriage member 12, having slide loops 13 to embrace the respective guide rods. Suitably connected with said carriage member 12, so as to be carried thereby, is a figure member 14; the

front face of which is suitably printed or lithographed to depict a Santa Claus of conventional appearance. Preferably, the means for connecting the figure member 14 to the carriage member 12 includes elastically flexible means, so that the figure, when moved up and down, will likewise be vibrated or agitated to a limited extent, whereby to increase the effect of life-like movements thereof. An illustrative form of connection of such kind comprises a stud 15 anchored to the carriage member 12 for forward projection therefrom, to which stud is in turn anchored a forwardly and freely projecting spring shank 16, to the free end of which the figure member 14 is suitably affixed.

Within the lower interior portion of the casing is mounted lower driving means for producing descending movement of the carriage member 12, and the figure member 14 carried thereby. This lower driving means comprises a transverse shaft 17 journaled in and between bearings 18 affixed to the casing bottom wall 2; said shaft being disposed behind but adjacent to the guide rods 11. Loosely mounted on said shaft 17, to turn freely thereon, is a lower reel or drum 19; the same being retained against shifting displacement between collars 20 which are affixed to the shaft. Upon said reel or drum 19 winds a lower pull cable 21 which is arranged to extend to the carriage member 12; to a lower attachment lug 22, with which the latter is provided, said pull cable is attached. Said reel or drum 19 is provided with a laterally projecting crank arm 23. Slidably mounted on said shaft 17, but suitably keyed thereto so as to turn therewith, is an annularly grooved clutch member 24 provided with a laterally projecting thrust piece 25. Said shaft 17 is suitably coupled with a clock-work or spring motor 26 which is mounted within the casing, preferably in affixed relation to a side wall 3 of the latter, through which exteriorly projects a manipulatable winding key 27 for winding the power spring (not shown) of said clock-work or spring motor.

Within the upper interior portion of said casing is mounted an upper driving means for producing ascending movement of the carriage member 12, and the figure member 14 carried thereby. This upper driving means comprises a transverse shaft 28 journaled in and between bearings 29 affixed to the casing top wall 1; said shaft being also disposed behind but adjacent to the guide rods 11. Affixed to said shaft 28, so as to turn therewith, is an upper reel or drum 30. Upon said reel or drum 30 winds an upper pull cable 31 which is arranged to extend to the carriage member 12; to an upper attachment lug 32, with which the latter is provided, said pull cable is attached. Said shaft 28 and the reel or drum 30 is rotated in cable winding direction by the stored tension of a power spring 33 which is helically wound around the shaft; one end of said spring being anchored to a fixed point, as e. g., by attachment to a bearing 29, and the other end of said spring being affixed to the reel or drum 30.

Means to automatically engage and release the clutch member 24 relative to the lower reel or drum 19 is provided and arranged so as to be actuated by the carriage member 12, as it reaches the upper and lower limits of its figure member carrying movements. In an illustrative form thereof, as shown, said means comprises a clutch shift lever, fulcrumed on a fixed pivot 34, and providing a lower arm 35 and an upper arm 36. The extremity 37 of the lower arm 35 is engaged

in the annular groove of the clutch member 24. The lower arm 35 of said shift lever is provided with a suitably shaped and located lower cam projection 38, and the upper arm 36 of said shaft lever is likewise provided with a similar suitably shaped and located upper cam projection 39. Said shift lever is disposed adjacent to the path of descending and ascending travel of the carriage member 12 on the guide rods 11. The carriage member 12 is provided with an angular extension 40 adapted to engage, at proper times, the shift lever cam projections 38 and 39.

When the figure member 14 and its carriage member 12 are disposed at the upper limit of movement, the figure 14 appears through the opening 10' and behind the depiction of the sleigh 10, thus providing the illusion that Santa Claus is seated in the sleigh (see Fig. 1). When thus occupying such upper limit of motion, the extension 40 of the carriage member 12 engages the cam projection 39 of the shift lever 35-36 so as to swing the latter clockwise, and thereby move the clutch member 24 into driving relation to the lower reel or drum 19 (see Fig. 2). Assuming that, under these circumstances, the clock-work or spring motor is wound up so as to transmit power to the lower shaft 17, thereupon said shaft is rotated to in turn rotate the clutch member 24 in a direction which (as shown) is anti-clockwise. As the clutch member revolves, its thrust piece 25 engages the crank arm 23 of the reel or drum 19, and thus revolves the latter so as to draw down and wind up thereupon the pull cable 21. The down pulling motion of the pull cable 21 is transmitted to the carriage member 12, whereby the same, and the figure member 14 carried thereby, is caused to slide downward on the guide rods 11. Such descent of the figure member causes the same to disappear from behind the upper opening 10' and consequently furnishes the illusion of Santa Claus leaving the sleigh 10 for descent through the chimney, until upon arrival of the figure member at its lower limit of movement, the same is disclosed through the lower opening 7, and Santa Claus appears to arrive and stand within the fireplace 5.

As the carriage member 12 is moved downward on the guide rods 11, the upper pull cable 31 is pulled down so that in unwinding from the upper reel or drum 30 it imparts rotary movement thereto and to its shaft 28, thereby winding the spring 33 so as to induce torsional tension therein, and thus store energy for later rotating said reel or drum 30 in direction to wind up the pull cable 31.

As the carriage member reaches the limit of its descending movement, its extension 40 is carried into engagement with the cam projection 38 of the shift lever 35-36 so as to swing the latter anti-clockwise, thus shifting the clutch member 24 so as to release the lower reel or drum 19. Upon this occurrence, the stored energy of the spring 33 becomes effective upon the upper reel or drum 30 and its shaft 28, thereby revolving the reel or drum 30 clockwise, and thus winding up the pull cable 31. The upward pull of the cable 31 effects an ascending movement of the carriage member 12 and the figure member 14, so that the latter disappears upwardly out of the fireplace, and reappears through the upper opening 10' behind the sleigh 10, thereby appearing to have ascended the chimney and again reentered said sleigh 10.

As the carriage member again reaches its upper limit of movement, its extension 40 again rides

into engagement with the cam projection 39 of the shift lever 35-36, thereby swinging the latter anti-clockwise, and thus again throwing the clutch member 24 into operative driving relation to the lower reel or drum 19, whereupon the above described operations are repeated, until the power of the clockwork or spring motor 26 is exhausted and required to be rewound.

While I have described the clutch driven reel or drum as operated by a lower clockwork or spring motor shaft and the upper reel or drum as operated by the spring 33, such arrangement may be reversed so that the former is located within the upper end of the casing and the latter within the lower end of said casing.

In order to accompany the action of the toy with audible sound suggestive of sleigh bells, a bell 41 is supported upon a spring arm 42 adjacent to an end of one of the shafts (e. g. the shaft 28 as shown). Said spring arm 42 is provided at its free end with an angular extension 43. Affixed to the shaft end is an angular striker arm 44 adapted to be revolved thereby. As the striker arm 44 revolves, it moves into and out of contact with the extension 43 of the spring arm 42, thereby agitating the same, and thus imparting motion to the bell 41 so as to effect sounding of the same in company with the descending and ascending movements of the Santa Claus figure.

While I have described the make-up of the mechanical toy of this invention in a form wherein the figure member represents a Santa Claus arranged for descending and ascending movements relative to a simulated fireplace and its chimney, it will be obvious that figures and backgrounds simulative of characters other than Santa Claus and in different environments may optionally be employed for actuation by the novel movement controlling mechanism according to this invention.

Various changes in the devices and detail parts of the toy could be made without departing from the scope of this invention as defined in the following claims. It is therefore intended that all matter shown in the accompanying drawing and described in the preceding specification shall be considered as illustrative and not in a limiting sense.

I claim:

1. A mechanical toy comprising a stationary front portion, the external face of which bears depiction of a selected environment, said front portion having at least one opening there-through, guide means fixed behind said front portion and said opening, a figure member slidably mounted on said guide means for back and forth movements thereon toward and from said opening, power means to cause movement of the figure member in one direction, a second power means to cause movement of the figure member in the opposite direction, and means actuated by the arrival of the figure member at limits of its said movements adapted to automatically control said respective power means so as to effect alternated operation thereof.

2. A mechanical toy comprising a stationary front portion, the external face of which bears depiction of a selected environment, said front portion having at least one opening there-through, guide means fixed behind said front portion and said opening, a figure member slidably mounted on said guide means for back and forth movements thereon toward and from said opening, a rotatable reel adjacent to one limit of movement of said figure member having a pull

cable attached to the latter, a power driven shiftable clutch cooperative with said reel, a second reel adjacent to the other limit of movement of said figure member also having a pull cable attached to the latter, a torsional spring for driving said second reel, and clutch shift means adapted to be actuated by arrival of the figure member at limits of its movements, whereby to automatically engage and disengage said clutch with said first mentioned reel to effect alternated operation of said respective reels.

3. A mechanical toy comprising a stationary front portion, the external face of which bears depiction of a selected environment, said front portion having at least one opening there-through, guide means fixed behind said front portion and said opening, a figure member slidably mounted on said guide means for back and forth movements thereon toward and from said opening, a power driven shaft adjacent to one limit of movement of said figure member, a shiftable clutch keyed on said shaft so as to be driven thereby, a reel rotatable on said shaft, a pull cable attached between said reel and figure member, said clutch and reel having cooperative means engageable to drive the latter from the former whereby to wind said cable to move the figure member in one direction, a second shaft adjacent to the other limit of movement of said figure member, a second reel on said latter shaft, a second pull cable attached between said figure member and said second reel, torsional spring means adapted to be tensioned by cable unwinding rotation of said second reel whereby to store energy for rotating the latter in cable winding direction so as to move said figure member in the other direction, and clutch shift means adapted to be actuated by arrival of the figure member at limits of its said movements whereby to automatically engage and disengage said clutch to effect alternated operation of the respective reels.

4. A mechanical toy as defined by claim 1, wherein the external face of the front portion thereof bears depiction of a fireplace and its chimney, the opening of said front portion being registered with the back of the fireplace picture, and wherein the figure member bears depiction of a Santa Claus.

5. A mechanical toy as defined by claim 2, wherein the external face of the front portion thereof bears depiction of a fireplace and its chimney, the opening of said front portion being registered with the back of the fireplace picture, and wherein the figure member bears depiction of a Santa Claus.

6. In a mechanical toy as defined by claim 3, wherein the external face of the front portion thereof bears depiction of a fireplace and its chimney, the opening of said front portion being registered with the back of the fireplace picture, and wherein the figure member bears a depiction of a Santa Claus.

7. A mechanical toy as defined by claim 1, wherein the lower portion of the external face of the front portion bears depiction of a fireplace and its chimney, said front portion having a lower opening registered with the back of the fireplace picture through which the figure member is exposed when disposed at its lower limit of movement, and wherein the upper portion of the external face of said front portion bears depiction of a building roof and superposed pictured reindeer drawn sleigh, said front portion having a second opening above the sleigh pic-

ture through which the figure member is in part exposed when disposed at its upper limit of movement, and wherein the figure member bears depiction of a Santa Claus.

8. A mechanical toy as defined by claim 2, wherein the lower portion of the external face of the front portion bears depiction of a fireplace and its chimney, said front portion having a lower opening registered with the back of the fireplace picture through which the figure member is exposed when disposed at its lower limit of movement, and wherein the upper portion of the external face of said front portion bears depiction of a building roof and superposed pictured reindeer drawn sleigh, said front portion having a second opening above the sleigh picture through which the figure member is in part exposed when disposed at its upper limit of movement, and wherein the figure member bears depiction of a Santa Claus.

9. A mechanical toy as defined by claim 3, wherein the lower portion of the external face of the front portion bears depiction of a fireplace and its chimney, said front portion having a lower opening registered with the back of the fireplace picture through which the figure member is exposed when disposed at its lower limit of movement, and wherein the upper portion of the external face of said front portion bears depiction of a building roof and superposed pictured reindeer drawn sleigh, said front portion having a second opening above the sleigh picture through which the figure member is in part exposed when disposed at its upper limit of movement, and wherein the figure member bears depiction of a Santa Claus.

CASPER KREUTZER.
